DOWELING JIG

David C. Morton, Richmond, Va.

Application May 23, 1940, Serial No. 336,810

14 Claims.

(Cl. 77—62)

This invention relates to certain improvements in craftsman's tools or implements, having reference to that class of devices known as "doweling jigs" which are designed for use in gauging and forming dowel-pin joints between the parts of structural manufactures such as cabinets and the like. More particularly it pertains to special devices of said kind and to methods of using or employing the same in constructing various articles and objects of an assembly nature.

An object of the invention is primarily to provide means by which the individual cabinet-maker or other article-constructing craftsman engaged in small piece-work business can economically compete with the larger business manufacturer in the making of high-grade furniture and other structural objects, by considerably reducing the amount of work and time necessary to form proper joints between the parts of such structures to be fitted together, it being well-known that the ordinary craftsman lacking costly machinery and other essential facilities for quantity production is obliged to charge relatively high for the labor of his hand work requiring great precision and care.

Another object is to provide an improved hand-tool device for locating and forming connective joints between the parts or pieces of different structural articles with the greatest facility and precision, which device will be easily manipulable and adaptable to almost any edge or surface upon which a joint is to be made, regardless of its angle or extent. Stated more specifically, the purpose is to provide a tool with which to secure an accurate alignment of dowels in the joints or between the parts of any material susceptible of being drilled by standard twist drills and, in cases such as wood where there is a distinct grain, to effect joints with the component parts disposed directionally with, against or angularly to the grain, or in combinations of with, against and angularly to the grain. In this connection it is proposed to substitute a series plurality of dowels for the usual tenon and mortise of the joints, for two material reasons; first, because tenon and mortise joints are difficult to form with sufficient accuracy to have the requisite close fit, even by the most skillful craftsman, and, second, because joints of closely spaced dowels have been found to have a stronger hold and are much more easily formed and close-fitted. Moreover, a closely spaced series of dowels actually provide a larger holding surface than a tenon and mortise joint of the same cross-sectional extent.

A further object is to eliminate the necessity for measurement and line to line adjustment in forming the joints, or to incorporate these factorial attainments fundamentally into the tool itself, so that not only will the craftsman be en-

abled to work with minimized labor and expedition, but an unskilled worker or even a novice can form the required joints between different assemblage parts of a structure with absolute accuracy, such that corresponding parts of the same can be interchanged one with another in perfect fit together. In other words, it is designed to attain an accurate alignment of dowel holes in the different separate parts or pieces of 10 an assemblage structure without the need of any measurement as by ruler, scale or gauge and certainly without need of any laboriously schematic or precisionary measure by such instruments, such need being removed by inherent capabilities 15 of the tool so that identical location of holes in the various pieces is attained even more accurately than by hand measure.

Other objects and the particular advantages of the invention will be set forth or readily appear from the following description with reference to the attached drawings, which illustrate one practicable embodiment and form of the same, with modifications, as applied and used in connection with different constructional members or parts.

In said drawings:

Fig. 1 is a perspective view of the basical device or tool;

Fig. 2 is a perspective view of an extension attachment substitutional for one of the component elements and forming a part of the complete device;

Fig. 3 is a perspective view corresponding to Fig. 1 showing said basical device enlarged in height by another attachment applied thereto;

Fig. 4 is a side elevation, as viewed from the left side of Fig. 1, of the device applied to a structural member such as a table leg for the drilling of joint holes in the latter, shown broken off;

Fig. 5 is an end elevation, from the left of Fig. 4, illustrating the clamping onto said member and showing the mode of hole drilling, a corresponding positioning of the member on the opposite side of the device being indicated in dotted lines;

Fig. 6 is a top plan view of Fig. 4, the structural member being again shown broken off;

Fig. 7 is a view similar to Fig. 5, representing the device applied to a thinner structural member such as a table leg stretcher or apron piece, with appurtenant shim-plate inserts for gauging the level of hole drilling therein;

Fig. 8 is a top plan view of one of the shim-plate inserts;

Fig. 9 is a fragmentary top plan view of the understructure or united legs and apron pieces of a table, illustrating the jointing of the parts as formed by the gaugement of the device;

Fig. 10 is a partly sectional side elevation view on the line 10—10 of Fig. 9;

Fig. 11 is a disassembled view of the device in side elevation, with the separated parts disposed in correct unitive relation;

Fig. 12 is an end view of the disassembled device or relatively separated parts;

Fig. 13 is a side elevational view of the device with attached extension or substitutional part of modified form, illustrating its application to an elongated structural member represented in dotted lines, the basical part of the device being shown broken off;

Fig. 14 is an end view, from the left, of Fig. 13;

Fig. 15 is an end view showing the device with adapting elements applied to a mitered or angular edge of a member, said edge in this instance being at a 45 degree angle.

Fig. 16 is a fragmentary partly sectional view of a joint formed at a 45 degree angle;

Fig. 17 is a view similar to Fig. 15 illustrating the device application to a 30 degree angle;

Fig. 18 is a plan view of a hexagonal member such as formed by the 30 degree angle jointing;

Fig. 19, also like Fig. 15, illustrates the device application to a 22½ degree angle;

Fig. 20 is a plan view of an octagonal member such as formed by the 22½ degree angle jointing;

Fig. 21 is an end view similar to Fig. 15 illustrating an adaptation of the device to the mitered or angular edge of a member such as a section of a circular column;

Fig. 22 is an opposite end inverted view of the device as it may be employed to form a joint with a metal insert or inlay such as is common in modernistic furniture;

Fig. 23 is a fragmentary partly sectioned view of a joint including a metal insert as in the surface of a table top or the like;

Fig. 24 is a plan view of the joint illustrated in Fig. 23;

Fig. 25 is a view similar to Fig. 13 showing the device with extensional attachment applied to a greatly elongated structural member and indicating its mode of use in forming joints at different stages or distances therealong;

Fig. 26 is a plan view illustrating a modification and adaptation of the device to the formation of joints upon a large surface, or at some distance from the edge of a member, as when another member is to be applied in superposition thereon;

Fig. 27 is a similar view illustrating the use of the device in forming corresponding joints in the superpositional member;

Fig. 28 is an end view of Fig. 27;

Fig. 29 is an end elevation of the large surface and superposed member joined together;

Fig. 30 is a detail plan view of an attachment part adapting the device to the flat surface use illustrated in Figs. 26 to 29;

Fig. 31 is a detail view of one of the spacer parts used in this modificational arrangement; and

Fig. 32 is a plan view of a further modification of the device adapted to form joint perforations on a flat surface along an angular edge.

Referring first to Figs. 1 to 3, the illustrative device or jig comprises a T-shaped block designated generally by 10 and hereinafter called the "mandrel." This block is made of metal such as iron or low expansion steel, and for a purpose later explained, is formed preferably in two plate parts, i.e. with the center angle-forming portion

10^a removable from the crossing main portion 10^b on which the block ordinarily rests. In this instance, the angle plate part is slide fitted into the main plate part, where it is held by securing screws 11 extended through the bottom (see Figs. 4 and 5 or 11 and 12). It is desirable to make such fitting possible in only one end-wise relation, as by locating said securing screws slightly different distances from the main plate ends, so that the angle plate cannot be reversed in position, for the reason that identical gaugements are best assured by having the same ends always together.

Said angle plate or portion 10^a has a longitudinal series of closely spaced circular holes 12 extending transversely therethrough. These are of a size corresponding to the dowels to be used in the jointing and are advantageously numbered consecutively upon opposite sides of the plate, beginning at the end—being the right one in Fig. 1—from which the gauging is intended to be taken. They serve both as guides for a drill or other boring tool and to locate or center the points at which dowel recesses are to be formed in a member to be jointed. To this end said holes are formed in the plate at that level or distance above the main plate surface which will automatically gauge the recess formations or drill borings the correct distance from the edge of the member. If so desired, these guide holes may be formed in staggered arrangement along the length of the plate instead of in the straight line arrangement shown, this being largely a matter of choice or preference. The principal advantage is to be gained from arranging them as closely together as possible without likelihood of splitting or weakening the material by adjacent borings therethrough, but in cases of such liability the borings can of course be simply restricted to alternate holes in the series.

The main plate or portion 10^b is provided with corresponding bearing plates 13 on opposite sides of the center angle portion. These bearing plates are secured thereon as by screws 14 countersunk in the plates and are intended to be loosenable quickly so as to admit or release a shim or raising plate thereunder if desired. It will be noted that the holes into which said screws 14 fit (see Figs. 4 and 5 or 11 and 12) extend all the way through the main plate and are countersunk at the bottom ends. The reason for this will be explained later. Beneath said bearing plates, properly fitted shim or raising plates 15 are shown applied in the organization of Fig. 1. These shim plates are used in certain cases where it is desired or necessary to gauge the drilling of the dowel recesses a lesser distance from the edge of a member, as for instance when an off-set is to be made between jointed members. Said shim plates are conveniently made in the form separately illustrated in Fig. 8, i. e. with open-ended slots 16 in one side receptional to the screws 14, so as to be applied and withdrawn sidewise with ready ease. More will be said about these later. In connection with the bearing and shim plates just described, it is desirable that both shall bear marking such as "Left" and "Right" to indicate upon which side of the angle portion they correctly belong, so that they may always be restored to the identical position after removal for any purpose.

At the end of the T-shaped block or mandrel from which gaugement is to be made, a right-angular abutment is provided as by an annular

plate 17 extending beyond opposite sides of the center part and which in effect forms a trihedral angle with the block upon each side of the same. Said abutment plate hereinafter called the "stop" disc or collar is connected to one end of the center part or plate portion 10^a and is intended to be extensible axially therefrom. In the organization of Fig. 1 and as better illustrated in Fig. 11, it is shown to comprise a fixed member, in the form of a knob, against the end of said plate, secured thereto by a threaded shank 17^a screwing into a screw-hole 18 in the latter. This arrangement is suitable to short work or structure pieces in which only one joint is to be formed. Alternatively, to accommodate longer work or pieces in which more than one joint is to be formed, this stop disc may comprise a collar adjustably positionable along an extension rod 19 secured in the end of the plate part. Such an alternative arrangement is illustrated in Fig. 2, wherein the stop collar is shown to be slidably adjustable on the rod 19 having a threaded tip 19^a adapted to be screwed into the hole 18 of said plate part in place of the threaded shank 17^a. This alternative arrangement of course is a mere substitution and equivalent of the one for the other. It is in fact the preferred form in its provision for extensibility of the stop, as first indicated, and is intended to constitute a part of the device, with the first described form as a mere substitution on occasion. It will be evident that the extensibly adjustable collar stop bears exactly the same relation to the mandrel as the fixed stop secured thereto; that is, it will slide upon its rod close against the mandrel end and therewith form the same trihedral angle. Hence, if so desired this extensional attachment may be permanently applied to the mandrel in lieu of any fixed stop and thereby eliminate substitution and interchanging.

If so desired, a duplicate screw-hole 18' may be provided in the opposite end of the plate part 10^a for alternative attachment of the described stop or abutment provision at that end, but as already indicated it is deemed preferable for identical correspondence or accuracy purposes to gauge all formations from one end only and for such reason said opposite end duplicate hole is shown to be closed against ordinary use by a plug screw 20.

Means for clamping the device to the work, or vice versa, is advantageously provided by bars 21 screwed into the top of the center plate 10^a (see Figs. 11 and 12) and supporting slidably adjustable arms 22 fitted thereon, which arms in turn carry adjustment screws 23 in their free ends. Said arms are securable in any position on said bars by simply tightening the clamping screws 24 at their back ends and may be swung around to either work engaging side of the mandrel. The adjustment screws in their free ends are similarly tightenable against the work by turn movement theretoward and have foot plates 25 on the inward ends of the same to prevent bruising or penetration into the work.

When it is desired to enlarge the height extent of said center plate 10^a, as for instance when working on wider than usual material or edges, an auxiliary plate 10^{aa} may be fitted thereon as shown in Fig. 3. This auxiliary plate, made with its edges and opposite surfaces flush therewith, may be formed with a corresponding series of drill-guide holes 12' therethrough and with corresponding stop-extension screw-holes 18 and 18' in its ends. It is merely mounted on the main

center plate, or interposed between said main plate and the clamp-supporting bars 21, and may be very expediently so applied by simply extending said supporting bars clampably therethrough between adjacent guide holes as indicated in Fig. 15. Of course any other preferred means of securing in place to the main center plate may be used instead, as for instance a direct bolting thereto, in which event the clamp supporting bars 21 would be screwed into the top of this auxiliary plate instead of the main plate itself.

Figs. 4 to 6 show the device applied to work comprising a structural member 26 such as a table leg. In side, end and plan view it is shown 15 clamped to said member with the latter correctly fitting close in the angle thereof against the stop disc 17 at one side. Thus positioned, the work member is receptive to accurate drilling in one side through the guide-holes 12, as indicated 20 in Fig. 5. A drill 27 is represented in applicative position for the drilling and a hole drilled thereby is represented in the dotted lines designated by 28. This drilling is automatically gauged to the proper level or distance from the member's 25 edge by the height of said guide-holes above its rest, or, more correctly stated, by the level to which the bearing plates 13 are disposed below said guide-holes. The drilling itself is accurately regulated by the guide-holes, directing the 30 drill passage therethrough, so that it can neither be done off-center nor at a slant. Opposite drilling of identical holes, or in corresponding location in a different side, is attained by applying the work member to the opposite side of the 35 device or mandrel. In dotted lines said member 26 is shown positioned upon the opposite side for like drilling through the opposite ends of the guide-holes and an oppositely drilled hole 28' such as would be thus made is represented in 40 dotted lines in the upper side of said member. Thus a member need merely be turned from one side to another for the opposite drillings desired therein.

Drill borings in the member may be made 45 through each of said guide-holes, which is ordinarily preferred for the greatest strength of the joint, or they may be made through any selected holes of the series. They are numbered consecutively for convenience of identifying those 50 used in such a selection. In Fig. 6 for instance the drillings are shown to be made through alternate holes numbered 2, 4 and 6. The same ones must of course be used for the jointing of any two pieces together. Insofar as possible, the 55 spacing between said holes, center from center, is made exactly identical. But with this device, used as intended, it makes no difference whether they are spaced absolutely equally or not. Accurate alignment and fit of the joints will result 60 if they are unequally spaced, or even if they are variably spaced apart. The reason for this will be explained.

Assume for example that the craftsman is 65 constructing a table. He first forms the legs, apron pieces, stretchers and top pieces and lathes them to accurate dimension and correspondence, so that each piece will conform exactly with its duplicates. He then decides how he desires to 70 arrange the pieces and which ends or surfaces he wishes to join together and will probably mark said ends for subsequent guidance. Next he would apply the device to each of the legs along their designated edges at the designated top end and drill holes in adjacent sides thereof as illustrated and already described in Figs. 4 to 6.

Thus each of the legs will be correspondingly drilled with exactly duplicated dowel holes in each of two sides.

The apron pieces are next correspondingly drilled oppositely in their opposite ends, as illustrated in Fig. 7. These pieces, such as represented by the member 29, are usually of a lesser thickness than the legs and are properly set in a slight distance from the outer edges of the latter, for which reason shim plates 15, hereinbefore described and illustrated in Fig. 8, will be inserted under the bearing plates 13 to off-set or lower the level of the drillings therein so as to automatically provide for such set-in when jointed into place. Also, in the opposite end drilling, the designated top edge of the pieces will be placed against the stop disc 17 on each side of the mandrel so as to ensure that the joint makes an absolutely level and close fit with the top of the legs. A reversal or turning to opposite end drilling may and oftentimes will cause an inaccurate fit or misfit. The said apron pieces thus prepared may now be jointed with the legs, as represented in Figs. 9 and 10, by insert of the proper dowel pins 40 to fit in or between the holes 28 and 28' formed in each, whereupon automatically they will be correctly positioned with an accurate close fit and with the proper set-in relation to the leg edges indicated by the corners x. However, before any of the parts are put together they should all be fully prepared so as to be assembled at the same time.

The stretchers next to be joint formulated are oppositely drilled in their opposite ends exactly the same as the apron pieces. They, like said apron pieces, fit between the legs with a set-in from the latter's outward edges as would also be illustrated by Fig. 9.

To provide for said stretchers, the legs must be correspondingly drilled also further down or below the jointing level of the apron pieces. This requires use of the extensible attachment of Fig. 2 in substitution for the fixed stop of the Fig. 1 organization, with reference to which the description thus far has been confined. Determining at what level or distance down the legs said stretchers shall be jointed thereto, the craftsman slides the adjustable collar stop 17 outwardly upon its rod 19 to a point permitting the mandrel to be brought into position, downwardly or lengthwise of the legs, at said level thereon. In other words, he extends the stop away from the mandrel to the point where the mandrel may be positioned correctly on the legs with the top ends of the latter bearing against said stop, correspondingly to the described instance of the fixed stop. He then secures the stop at said extended point, as by tightening the set-screw 17b. Clamping the device in this adjusted extension position as previously described, the worker proceeds as formerly to drill a second series of joint holes in the proper edges or sides of each of the legs, or correspondingly to those first drilled thereabove for the apron pieces. Thus the stretchers like the apron pieces, as illustrated in Figs. 9 and 10, may be jointed in place between the legs.

Similarly, the top sections are drilled and jointed together along their butting longitudinal edges, the mandrel being extensionally adjusted to each subsequent position of joint formation lengthwise of the same. Ordinarily there will be at least three joint formations between the sections along their full length and this will call for three different positionings of the mandrel thereto, in

each of which they are oppositely drilled in the proper relation. The jointed top is fastened as usual to the assembled understructure of the table by suitable dowel joints formed with or without the aid of the device as preferred.

The dowels used in the jointing between the several parts are of course intended to be glue coated or glue secured in the recesses provided therefor. Said dowels, denominated by 40 throughout the several views, are preferably close fitted into said recesses or drilled holes so as to have a strong hold. In this connection, referring for illustration again to Fig. 10, the formed joints may be strengthened and in fact rendered virtually inseparable by drilling therethrough transversely in the pieces on opposite sides of the joint a very small hole and inserting a wire or pin 41 therein, serving to spike or lock the dowels against movement or loosening in either direction.

It will be noted that the gaugement and locating of all joints between the different parts or members is done from the same end or edge of said members, as well as from the same end of the mandrel. Every set or positioning of the mandrel for the dowel hole drillings in the correct opposed relation is determined by the stop 17 engaged against said limit of the members. This eliminates the possibility of error and ensures the formation of absolutely accurate or aligned and perfectly fitting joints, wherein the parts brought together meet close and tight in perfect level and squaring with each other. All need for actual measurement is also eliminated, the device itself automatically making or inherently including the necessary measurements and fixing the points for drilling identically in each of the members with absolute precision surpassing that even possible by hand rule or other gauge. The only particulars in which care is required to avoid faulty formations are to see that the mandrel is properly applied to each member and to be sure always to drill through the selected guide-holes for each joint.

The applicability and procedural use of the device in the construction of various other articles and structural objects will be apparent from the foregoing illustrative description. Of course the mandrel may be adapted to any length member for forming as many joints therealong as desired, merely by extending the length of the attached extension rod 19 as far as necessary and this may be done in sections or by jointing shorter lengths of rod together.

Referring now to the modification of Fig. 13, a sectionally formed extension rod 19 is shown provided with fixed station attachments or means for setting the adjustable collar stop 17 into different predetermined or previously occupied positions thereon. The purpose of this is that in performing certain kinds of work, such as duplicating previous constructions, the craftsman may find it necessary to shift the stop collar back and forth to different identical positions and such provision enables him both precisely and expeditiously to restore the stop to any particular position or setting that he may wish. In other words, he can establish and maintain fixed stations to which the stop collar may be alternately adjustable and, if so desired, he may make up any number of extension rods with such fixed stations attachable to the mandrel for different kinds of work. The said attachments or means comprise eccentric collars 42 screw-clamped or otherwise fixed securely upon the rod immediately behind

the points to which the stop collar is to be adjusted, so as to abut against said stop collar in the correct position of said points. In advance of each of said eccentric collars a split sleeve 43 concentric with the rod and of the same diameter as said eccentric collars is applied slideably on the rod. The stop collar 17 itself is bored to a larger size permitting it to be slipped or passed over both said eccentric collars and the split sleeves, but not over both at the same time. Thus, said stop collar may slide with or on either of the split sleeves along a length of the rod, but will be obstructed by the eccentric collars unless demounted or removed from said sleeves. In shifting to position at any one of these fixed points, the stop plate is passed alternately over the intervening split sleeves and eccentric collars, or vice versa. At the point where adjustment is to be made, it is slipped over the immediate split sleeve and moved back against the eccentric collar which is intended to abut it in the adjustment. Pressure against said eccentric collar brings the stop flush with the split sleeve on which it is mounted and its setting screw 17^b is then tightened to bind securely upon the sleeve, the latter contracting slightly upon the rod. In this position it is held until occasion for adjustment to another position as just described. One of the split sleeves, indicated as 43', located between the mandrel and the first fixed stop collar therefrom, may be formed as a nut mounted on the rod and tightenable against the mandrel as a lock therefor, onto which the stop collar may be engaged against the mandrel end in lieu of a directly connected stop disc or plate.

In said Fig. 13, the stop plate is shown gaugeably adjusted to the end of a structure member 26 which has previously been drilled with dowel holes and is ready for a subsequent drilling with the mandrel properly positioned at a new location or level for joint formation. Fig. 14 is an end view of this adjusted application, looking from the left end of Fig. 13.

Figs. 15 to 20 illustrate the use of the device in forming mitered or angular joints. This involves the drilling of edges which are not fitable in the angle of the mandrel against the sides of the center plate portion 10^a thereof and necessitates special adapters or clamping elements. Said adapters or clamping elements comprise wedge-shaped blocks 44 and 45 having an angulation depending upon the angle of the edge to be drilled, between which the structural member or piece 26' is clamped to the device, or vice versa, with its said edge flush against said center plate portion 10^a of the mandrel. The lower of these clamping blocks, viz. block 44, is secured upon the mandrel by screws 46 engaged therewith upwardly through the base portion of the mandrel within the holes normally occupied by the screws 14 holding the bearing plates 13 in place, the said substituting screws 46 being of a diameter less than the diameter of the screws 14 and serving in lieu thereof to hold said plates in place together with said clamping block. The upper of said clamping blocks, viz. block 45, is recessed in its top to receive the foot plates 25 of the screws 23 which accordingly hold it in place. If the member to be drilled is wide or thick enough to require it, the height extent of the central member 10^a is increased by the attachment of an auxiliary plate 10^{aa} thereto as previously described (see Fig. 15). Thus, the structural member is securely clamped between the

two angled blocks in position for drilling as previously described.

Fig. 15 illustrates the above described adaptation of the device to a 45 degree edge or mitre and Fig. 16 illustrates the joint formed by the drilling of like structural members or pieces 26'. Fig. 17 illustrates a like adaptation to a 30 degree mitre or edge, while Fig. 18 represents a formation such as the cross-section of a hexagonal column which would be formed by the jointing of similar structural pieces 26' of said angulation. Similarly, Fig. 19 illustrates the same adaptation to a 22½ degree mitre and Fig. 20 represents a member, such as the cross-section of a column, which would be formed by the jointing of like members 26' having the latter angulation or edge mortising.

A modification of the above described adaptation to mitre jointing is shown in Fig. 21, where in the member 26' is curved on one side as for the production of a circular column. In this modification or particular adaptation, the lower clamping block 44 is omitted and one of the regular bearing plates 13 is replaced with a substitute plate 13' of greater width or lateral extension having a marginal flange 13^a depending therefrom. Said flange carries a plate 47 clampable in vertical adjustment thereagainst as by bolts 48 extending through slots formed therein engaged by the wing nuts 49. This plate serves as a support against the curved under side of the member which is rested intermediately thereupon with one end in the angle of the mandrel and is oppositely clamped by the upper clamping block 45 so as to be firmly supported for the drilling operation in its mitered or angular edge. It will be obvious that the plate 47 needs only to be raised or lowered to accommodate members of different curvature. As previously described, the device is moved to different positionings along the edge of the member for different locational stage drillings longitudinally, as illustrated more plainly in Fig. 25. Here an elongated member 26' is shown with four stages of drillings along one longitudinal edge and with the mandrel device 10 in position for the fourth stage drilling along the opposite edge. It will be noted that all positionings or gaugements are taken from the same end of the member, namely, the left end, where the stop collar 17 is shown bearing against the edge of the same.

Figs. 22 to 24 illustrate how the device may be used to include a metal insert or trim piece into a joint so as to be wholly secure and flush in the material. Referring first to Fig. 22, the device is shown inverted so as to engage the work upon its top surface rather than the lower surface as ordinarily, but this is not essential as it might also be done with the device in the normal or non-inverted position and simply inverting the work instead if that should be necessary. Here the structural member 26 is shown recessed to receive a metal strip insert or inlay 50 along the jointing edge. The said insert is made flush with the top surface of the member as it properly should be for proper finish and appearance. With the member and insert together in this position against the side of the central plate portion 10^a of the device, the joint holes are drilled as previously described through the metal insert as well as into the structural member itself, thereby providing for the dowel pins of the joint to extend entirely through the insert. Such a drilling is indicated in dotted lines designated by 28''. Of course an opposite drilling 28''' is

made in the adjacent member 26" to be jointed with the former. In addition, the two members are preferably drilled a second time for direct jointing to each other as indicated by the second joint holes 28 and 28' below the first ones, thereby assuring a stronger and more secure joint between the two members with the metal insert. In this connection, the central plate portion 10^a of the mandrel can of course be formed with two series of drill-guide holes at different levels to provide for these two different drillings at the same time, or without necessity of applying the device a second time to the members. Such a provision is indicated by the dotted line representation of guide-holes passing through said plate portion at the two separate drilling levels. Fig. 23 illustrates in end section the joint thus formed between the members with the metal insert 58. It will be noted that the dowels 40' passing through said insert hold it secure at both sides within the inlaid member at both sides of the joint, while the ordinary dowels 40 extend only into the members themselves. Fig. 24 illustrates said jointing in plan view, from which it will be appreciated that the metal strip insert lies completely flush with the top surfaces of the members as well as absolutely secure and tight in place.

A modificational adaptation of the device to use in forming joints between large surface members or members superimposed upon a large surface, involving the drilling of holes over a large surface or at some distance from the edges of a member, is illustrated in Figs. 26 to 32. Referring first to Figs. 26 and 27, let it be assumed for example that two panel members 51 and 52 are to be joined one upon the other. The center plate portion 10^a of the mandrel is removed from the main plate portion 10^b thereof, as previously described herein, and is used alone with an attached extensional stop rod 19, preferably a rod formed with fixed stations as hereinbefore previously described. This center plate portion 10^a is in this instance laid flat upon the surface to be drilled and is of course gauged to position longitudinally of said surface for the several or successive drillings by said extension rod and its stop collar 17 as before. However, in place of the clamping means previously described, a substitute and modified clamping arrangement is provided by a pair of rods 53 screwed into the holes of said plate normally occupied by the bars 21 which extend transversely across the surface to and beyond the opposite side. This pair of rods 53 is engaged by a plate 54 slidably adjustable thereon against said opposite side of the surface and set to different positions thereon by clamp elements 55, similar to the stop collar 17, therebehind formed advantageously as a part thereof (see Fig. 30). In this connection, said rods are desirably provided with fixed stations, similarly to the extension rod 19, to which said plate can be alternately adjusted like the stop collar 17. Thus, it will be seen that the substituted clamp attachment provides a combined gauge and guide for the mandrel part at right angles to the primary gauge attachment. The mandrel part is accurately adjusted to different positionings of drilling by the two gauge attachments working against opposite or right-angularly related edges of the surface in the manner illustrated in the drawings. As before, all primary adjustment is made from the same end or surface of the member to be drilled. In this instance, single holes are shown to have been

drilled through the same guide hole of the mandrel part along one longitudinal edge and one transverse edge of the surface.

The superimposed surface or member is then 5 oppositely drilled with identical holes by inverting or oppositely arranging the device on the under side thereof as illustrated in Fig. 27 (see also Fig. 28). However, inasmuch as this superimposed member is of lesser dimension than the lower 10 surface first drilled, adjustment for this difference of marginal width is made by interposing gauge plates 56 (see Fig. 31) on the rods 53 between the plate 54 and the edge of the surface against which it is applied. This automatically 15 disposes the hole drillings to the proper distance from the margins so as to make them register exactly with the holes previously drilled in the lower surface, said gauge plates being of the same thickness as the marginal difference between the 20 two members fitted together. Fig. 29 illustrates the jointing of the two members by the inserted dowels after the drilling of the two correspondingly as described.

Fig. 32 illustrates this described device or arrangement applied to a surface or member 57 having an angular edge. In this instance, an angular adapting plate 58 is pivoted at one end to the gauging guide plate 54 and bears against the angular edge of the member in place of said 30 former plate itself, being adjusted thereto by the link arm 59 connected between their opposite ends holding the same in fixed position by the clamp screws 60. Thus, as formerly, the plate 54 is adjusted upon the rods 53, except that the attached 35 angle compensating plate 58 instead bears against the edge of the surface. In this adjustment use of the device it will ordinarily be feasible to drill only one hole for each setting or positioning of the mandrel part, although as before the drilling 40 should always be made through the same guide hole of said part.

It will be understood, as previously stated, that in all uses of the device, the holes for jointing can be drilled through any one or more of the series 45 of guide holes formed in the center plate portion 10^a of the mandrel. However, it is essential that in any one piece of work, the dowel holes always should be drilled through the same guide holes of the mandrel. Thus there can be no discrepancy 50 which might cause an imperfect fit or jointing and if the guide holes in said mandrel should be unequally spaced apart one from the other, it will make no difference in the jointing because identical hole drillings in opposite edges or surfaces 55 of the structural members will always be brought into register.

The various possible uses and advantages of the invention will doubtless be appreciated from the foregoing description of different ways in 60 which it can be used in the jointing of variously formed members for different constructions. Apart from the adaptability and facility with which the device may be employed to form accurate joints between members, it eliminates all 65 need for measuring or meticulous computation as to where and in what dimension a joint shall be formed, having reference not only to the usual tenon and mortise joint but also to dowel jointings as they have hitherto been formed. The 70 device automatically produces a precise jointing of a very strong kind—stronger indeed than the ordinary tenon and mortise joint, because the several dowels fit close and tight within their recesses and will in most instances be brought very

close together. The device itself costs little to construct or buy and the associated attachments or appurtenant parts are likewise most inexpensive. Accordingly, the small-business cabinet maker or other craftsman working alone or with very little help is able to construct various articles in very much less time and can compete favorably with the large manufacturer having expensive machinery and precisionary equipment.

It will be understood that various changes in form, arrangement and combination of the elements of the device can be made to suit different conditions without departing from the actual scope of this invention, so that the appended claims are not intended to limit the same to the specific form or arrangement as hereinbefore described and illustrated.

Having thus described my invention, what I claim as new and desire to secure by Letters Patent of the United States is:

1. A device for locating and forming dowel joints between structural members, comprising a cross-sectionally T-shaped metal block formed in two plate parts separable from each other, one of said parts forming the base on which the block normally rests and the other forming the center T'ing member at right angles thereto, said center T'ing part being provided with a longitudinal series of closely spaced drill-guide holes extending transversely therethrough along the length thereof, and a plate extensibly attached to one end of the center T'ing member of the block in a trihedral angle forming relation thereto providing a gauging stop abutment for the end of a structural member applied to the device, said plate being removable with the center T'ing part of the block when separated from said base part thereof.

2. A dowel joint forming device which consists in a cross-sectionally T-shaped metal block composed in two plate parts separable from each other, one of said parts constituting the central angle forming portion of the block and the other of said parts constituting the crossing main portion of the block on which it normally rests, said angle forming plate part being formed with a longitudinal series of closely spaced drill-guide holes extending transversely therethrough along the length thereof, and a plate attached to said angle forming part of the block at one end of the same in a position to therewith form a trihedral angle, said plate providing a stop abutment for the end of a structural member applied to the device for drilling and being adjustably extensible from the block end.

3. A dowel joint forming device, comprising a cross-sectionally T-shaped metal block formed in two plate parts separable from each other, one of said parts constituting the central angle forming portion of the block and the other of said parts constituting the crossing main portion of the block, said angle forming plate part being formed with a longitudinal series of closely spaced drill-guide holes extending transversely therethrough along the length thereof and having attached means for clamping a member therebeside against the main plate part on either side of the same, and a plate attached to said angle forming member at one end of the block providing a stop against which a member to be drilled is endwise positioned correctly therefor upon the device, said plate being adjustably extensible from the end of the block.

4. A dowel joint forming device, comprising a cross-sectionally T-shaped metal block formed in two plate parts separable from each other, one

of said parts constituting the base on which the block normally rests and the other constituting the center T'ing member at right angles thereto, said center T'ing part being formed with a longitudinal series of closely spaced drill-guide holes extending transversely therethrough along the length thereof, means for changing the top surface level of said base forming part of the block in relation to the longitudinal series of holes in the center T'ing part of the same, and a plate attached to one end of the block therewith forming a trihedral angle, said plate being attached to the center T'ing part and being extensible adjustably therefrom.

5. A dowel joint forming device, comprising a cross-sectionally T-shaped metal block formed in two plate parts separable from each other, one of said parts constituting the base on which the block normally rests and the other of said parts constituting the center T'ing member at right angles thereto, said center T'ing part being formed with a longitudinal series of closely spaced drill-guide holes extending transversely therethrough, an abutment plate at one end of the block positioned so as therewith to form a trihedral angle and constituting a stop against which the end of a member applied to the device is endwise positioned thereto, said abutment plate being extensible to adjusted positions from the end of the block, a rod secured in the end of the center T'ing part of the block on which said abutment plate is mounted slideably for extension, and means on said rod for adjusting said abutment plate to fixed positions therealong.

6. A dowel joint forming device, comprising a cross-sectionally T-shaped metal block formed in two plate parts separable from each other, one of said parts forming the base on which the block normally rests and the other forming the center T'ing member at right angles thereto, said center T'ing part being formed with a longitudinal series of closely spaced drill-guide holes extending transversely therethrough and having attached means for clamping a structural member longitudinally therebeside against the base part on either side of the block in position for drilling operation thereon, said clamping means constituting rods screwed into the top of said T'ing member, laterally extended arms slideably adjustable and clampable on said rods and screws carried by said arms in tightenable movability against the member to be drilled, and a plate extensibly attached to one end of the block in a trihedral angle forming relation thereto providing a gauging stop abutment for the end of a member applied to the device, said plate being mounted to the center T'ing part of the block so as to be removable therewith when the same is separated from said base part thereof.

7. A dowel joint forming device, comprising a cross-sectionally T-shaped metal block formed in two plate parts separable from each other, one of said parts forming the base on which the block normally rests and the other forming the center T'ing member at right angles thereto, said center T'ing part being formed with a longitudinal series of closely spaced drill-guide holes extending transversely therethrough and said base part being provided with surface plates on either side of the center T'ing part determining its level below the level of the drill-guide holes in said T'ing part, said plates being removably secured by screws extending through said base part of the block and being adapted to the in-

sert of raising shim plates thereunder to elevate its level below said holes, and a plate extensibly attached to one end of the block in a trihedral angle forming relation thereto providing a gauging stop abutment for the end of a member applied to the device, said plate being mounted to the center T'ing part of the block so as to be removable therewith when the same is separated from said base part thereof.

8. A dowel joint forming device, comprising a cross-sectionally T-shaped metal block formed in two plate parts separable from each other, one of said parts forming the base on which the block normally rests and the other forming the center T'ing member at right angles thereto, said center T'ing part being formed with a longitudinal series of closely spaced drill-guide holes extending transversely therethrough and having attached means for clamping a member longitudinally therebeside against the base part on either side of the block in position for drilling operation thereon, said clamping means constituting rods screwed into the top of said T'ing member, laterally extended arms slidably adjustable clampably on said rods and screws carried by said arms threadably projectable therethrough so as to be tightened against the member positioned on the base for drilling, and said base part being provided with surface plates on either side of the center T'ing part determining the rest level of a structural member thereon below the level of the drill-guide holes in said T'ing part, an abutment plate at the end of the block disposed to therewith form a trihedral angle and providing a gauging stop for the end of member applied to the device for drilling, and a screw element secured in the T'ing part of the block on which said plate is mounted and adapted to extensional adjustment therefrom.

9. A dowel joint forming device, comprising a cross-sectionally T-shaped metal block formed in two plate parts separable from each other, one of said parts constituting the base on which the block normally rests and the other of said parts constituting the center T'ing member at right angles thereto, said center T'ing part being formed with a longitudinal series of closely spaced drill-guide holes extending transversely therethrough, and a plate extensibly attached to one end of the block in a trihedral angle forming relation thereto providing a gauging stop abutment for the end of a structural member applied to the device, said plate being attached directly to the center T'ing part of the block so as to be separable therefrom and usable therewith independently of the base part of the block for gauging or locating and forming dowel joint holes over a wide flat surface.

10. A dowel joint forming device, comprising a cross-sectionally T-shaped metal block formed in two plate parts separable from each other, one of said parts forming the base on which the block normally rests and the other forming the center T'ing member at right angles thereto, said center T'ing part being formed with a longitudinal series of closely spaced drill-guide holes extending transversely therethrough, an abutment plate mounted at one end of the block in right angular relation to both of said plate parts thereof, said abutment plate providing a gauging stop for and against the end of a structural member applied to the device, and a rod on which said abutment plate is mounted for slide adjustment extensionally from the end of the block, said rod being secured in the center T'ing part of the block so

as to be removable therewith from the base part and usable therewith independently of said base part for certain dowel joint forming operations.

11. A dowel joint forming device, comprising a cross-sectionally T-shaped metal block formed in two plate parts separable from each other, one of said parts forming the base on which the block normally rests and the other forming the center T'ing member at right angles thereto, said center T'ing part being formed with a longitudinal series of closely spaced drill-guide holes extending transversely therethrough, an abutment plate mounted at one end of the block in right angular relation to both of said plate parts thereof, said abutment plate providing a gauging stop for and against the end of a structural member applied to the device, a rod attached to the center T'ing part of the block on which said abutment plate is mounted, and means on said rod for adjusting said abutment plate to fixed station positions thereon, said means constituting eccentric collars fixed on the rod immediately behind the points of fixed station positioning so as to abut the abutment plate in such positions and concentric split sleeves slideable on the rod in advance of each of said eccentric collars, the abutment plate being bored to size so as to pass or slide over each of said eccentric collars and concentric sleeves lengthwise of the rod but not over both simultaneously and being clampable on any one of said concentric sleeves against any one of said eccentric collars in fixed station position.

12. A dowel joint forming device which consists in a cross-sectionally T-shaped metal block composed in two plate parts separable from each other, one of said parts constituting the central angle forming part of the device and the other of said parts constituting the crossing main part of the device on which it normally rests, said angle forming part being provided with a longitudinal series of closely spaced drill guide holes extending transversely therethrough along the length thereof; means extending axially from one end of the angle forming part adapted to form a stop abutment for the end of a structural member applied to the device; and means on the device for clamping a structural member having a mitered edge thereon in such position that said edge is disposed flush against the face of the said center angle forming part of the device.

13. In a device as set forth in claim 12, said clamping means comprising a block secured on the main portion of the device and having its upper face disposed in a plane passing through the heel of the angle formed between the two separable parts of the device; one face of said structural member resting upon the said upper face of the block and with said mitered edge flush against the center angle forming part of the device; and a second block engaging the opposite face of the structural member; and means on the device for urging the second block towards the first block.

14. In a device as set forth in claim 12, said clamping means comprising a plate vertically adjustably mounted on the crossing main part of the device offset from the central angle forming part; and adapted to engage the underside of a structural member mounted in the device with its beveled edge flush with the face of the central angle forming part; a block engaging the upper face of said structural member; and means for urging the block towards the main crossing part of the device.
